CLAIM

The ornamental design for an animal collar, as shown and described.

DESCRIPTION

FIG. 1 is a perspective view of an animal collar, showing our new design;

FIG. 2 is a bottom view of the animal collar;

FIG. 3 is a top view of the animal collar;

FIG. 4 is a right view of the animal collar;

FIG. 5 is a left view of the animal collar;

FIG. 6 is a front view of the animal collar; and,

FIG. 7 is rear view of the animal collar.

The dashed lines in the figures represent stitching.
